INVENTOR

BY *Victor J. Evans*

ATTORNEY

WITNESS:

UNITED STATES PATENT OFFICE.

DAVID R. COTNER, OF PHOENIX, ARIZONA.

CHAIR.

Application filed October 5, 1925. Serial No. 60,555.

To all whom it may concern:

Be it known that I, DAVID R. COTNER, a citizen of the United States, residing at Phoenix, in the county of Maricopa and State of Arizona, have invented new and useful Improvements in Chairs, of which the following is a specification.

The object of this invention is the provision of a rocker support for chairs or the like for converting said chairs into rockers, swings, and that class of children's furniture known as "shoo-flys," etc.

A further object is the provision of a means of this character which permits of the free swinging of the chair attached thereto and which sustains the seat of the chair in normal horizontal position during the rocking motion.

A further object is the provision of a means for this purpose characterized by simplicity in construction, reliability and efficiency in practical use, and further wherein the construction is such that the same may be attached to any ordinary form of chair, settee, or the like.

To the attainment of the foregoing the invention consists in the improvement as herein described and definitely claimed.

In the drawings:—

Figure 1 is a side elevation of the improvement in applied position.

Figure 2 is a similar view of the improvement, the chair or the like being illustrated by dotted lines.

Figure 3 is a front elevation of the construction disclosed in Figure 1.

Figure 4 is a top plan view of the improvement.

In carrying out my invention I make use of a frame which includes spaced front uprights 1. These uprights are supported on wheels 2. Preferably the lower ends of the uprights are bifurcated to receive the wheels 2 therein, the pivot or axle for the wheels being indicated by the numeral 3. The uprights 1, at a suitable point below the top thereof, have laterally extending beams or bars 4. These bars may have their ends mortised in the uprights, and are likewise effectively secured to the uprights by upper and lower angle braces 5. Also supporting the bars 4 and bracing the same to the uprights 1 there are angle braces 6 secured to

the lower ends of the uprights and to the under faces adjacent the rear portions of the bars, 4.

Passing through aligning openings in the parallel bars 4 there is a shaft 7. Suitable stop means 8 are arranged on the shaft and contact with the inner faces of the bars 4 for holding the shaft from longitudinal movement. The shaft passes through uprights in the nature of leg members 9 which provide the rear elements of the improvement. The leg members extend a suitable distance above their pivotal connection with the shaft 7, and are of a less length than the standards 1. Secured on the lower ends of each of the legs 9 there is a rocker member 10. The upper and flat face of each of the rockers 10 has secured thereon the straight ends of angle braces 11, these braces being secured by means 12 to the leg members 9.

Journaled in suitable bearings 13 in the top of the standards 1, there is the straight upper portion 14 of a substantially U-shaped rod member or shaft. The parallel arms 15 of the member 14 are disposed out of frictional contact with the standards 1, the said arms 15 extending downwardly from the standards. The arms 15 have their lower ends offset outwardly, as at 15', and these offset portions are preferably threaded. The leg members 9, adjacent to their upper ends are provided with openings 16, through which pass pivots 17 that secure the said legs on the rear leg portions of a seat 18. The front legs 19 of the seat carrying member 18 are provided with apertures through which pass the angle and threaded ends 15' of the substantially U-shaped rod which in reality is in the nature of a crank shaft. Suitable bolts 20 are screwed on the ends 15' of the crank shaft.

It is obvious that any seat carrying element may be supported on the improvement in a manner as above described and thereby be converted into a rocking member. The normal position of the device is, as illustrated in Figure 1 of the drawings. In the movement of the chair, the rocker 10 being fulcrumed on a floor surface, rocks in the usual manner. This rocking movement will swing the legs 19, which being pivotally connected with the legs of the seat carrying member will move the same outwardly, as

disclosed by the dotted lines in Figure 2 of the drawings. A movement of the seat carrying member in an opposite direction will, of course, cant the rocker to an opposite angle to that disclosed in Figure 2, and thus the seat carrying member will be moved rearwardly. The seat carrying member may be propelled by such movement should it be further desirable, and while a swinging action is imparted to the said seat carrying member the seat thereof is at all times retained in its normal horizontal position.

The simplicity of the construction and the advantages thereof will, it is thought, be perfectly apparent to those skilled in the art to which such invention relates, when the foregoing description is carefully read with the accompanying drawings. It is, however, to be understood that I do not wish to be restricted to the material, size, proportion and other details of construction and may therefore make such changes

from the showing as fairly fall within the scope of what I claim:

Having described the invention, I claim:— 25

In a device of the class described, a frame, including uprights, wheels supporting the uprights, bars extending rearwardly from the uprights, brace means between the bars and uprights, leg members pivotally secured to the rear of the bars, rocker shoes supporting the legs, brace means between the rockers and legs, a crank shaft journaled on the top portion of the standards, having its depending parallel arms extending toward but 35 spaced away from the standards, and said arms terminating in outwardly directed threaded extensions, which latter are designed to be passed through the front legs of a chair or the like, and means for pivotally connecting the upper ends of the legs with the said chair or the like. 40

In testimony whereof I affix my signature.

DAVID R. COTNER.
